CLAIM

We claim the ornamental design for a bicycle frame, as shown and described.

DESCRIPTION

FIG. 1 is a top and front perspective view of a bicycle frame embodying our new design;

FIG. 2 is a bottom and front perspective view thereof;

FIG. 3 is a top and rear perspective view thereof;

FIG. 4 is a bottom and rear perspective view thereof;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a top plan view thereof; and,

FIG. 10 is a bottom plan view thereof.

1 Claim, 9 Drawing Sheets
